UNITED STATES PATENT OFFICE.

CHARLES E. BAKER AND EVERETT M. DE LONG, OF HARTFORD, CONNECTICUT, ASSIGNEES, BY MESNE ASSIGNMENTS, TO THE NEW BRITAIN MACHINE COMPANY, OF NEW BRITAIN, CONNECTICUT, A CORPORATION OF CONNECTICUT.

EXPLOSIVE-ENGINE.

1,154,475.

Specification of Letters Patent. Patented Sept. 21, 1915.

Application filed July 8, 1910. Serial No. 570,949.

To all whom it may concern:

Be it known that we, CHARLES E. BAKER and EVERETT M. DE LONG, each a citizen of the United States, and each a resident of 5 Hartford, in the county of Hartford and State of Connecticut, have invented a new Improvement in Explosive-Engines, of which the following is a specification.

Our invention relates to that class of engines in which the power to drive the piston is obtained from the ignition of a combustible charge within the cylinder, and the object of the invention is generally to provide a device of this class having novel features of 15 construction and operation.

One form of device embodying our invention and in the use of which the objects hereinabove set out may be attained is illustrated in the accompanying drawings, in 20 which—

Figure 1 is a view in central vertical section through an engine embodying our improvement. Fig. 2 is a view in vertical section on plane denoted by dotted line 2—2 of 25 Fig. 1, and with parts otherwise broken away to show construction. Fig. 3 is a view in horizontal section on plane denoted generally by dotted line 3—3 of Fig. 1.

An engine containing the features of improvement forming the subject-matter of this application may be of various types and embody different forms of construction and it may be applied to various uses. Such an engine is especially applicable for use in 30 motorcycle construction, and for this reason we have selected a construction of mount applicable to such a vehicle for the purpose of illustration and description of our invention herein.

40 In the accompanying drawings the numeral 6 indicates a portion of a lower frame part of a motorcycle secured to an upper frame part 7 in any suitable manner. A bracket 8 is located upon this part 6, said 45 bracket forming a support for one end of the lower section 9 of a crank case upon which the cylinders 10, 11 are supported. The crank case may be otherwise supported if necessary in any desired manner, but as 50 such support is not material to this invention further and detailed description is omitted herein. The upper section 12 of this crank case is firmly secured to the lower section, the two parts at their meeting faces

being formed to provide bearings for a 55 crank shaft 13. The sections of the case are also of a construction to provide crank chambers 14, 15 within which the cranks 16, 17 are located. The crank shaft, cranks and fly-wheel 18 may be of any suitable construction, which however is not essential to our present invention. The cylinders 10, 11 are secured to the upper section 12 of the casing immediately over the crank chambers 14, 15 which have openings to the interior of the cylinders for the passage of the pitmen 21, each of which is connected at one end to one of the pistons 22 and at the other end to one of the cranks 16 or 17.

The valves having means for separately 70 adjusting the pressure with which they bear against the valve seats form a feature of our invention. If such pressure of either valve is too great or too little the maximum effect will not be obtained; hence it will be 75 seen that in order to obtain the full efficiency of the engine the valves should have means whereby this pressure may be graduated to a nicety, and when the right pressure is obtained then it should be preserved. 80 Our construction affords greatest freedom of action for the valves, the bearing plates being readily accessible for the purpose of adjustment of the pressure of the springs.

The upper section 12 of the crank casing 85 contains an intake chamber 23 and main chambers having their inner ends divided by bearing plates 29 into valve chambers 24, 25 for intake or distributing valves, 26, 27 that control the openings from the intake 90 chamber to the valve chambers. Each of these distributing valves has a stem projecting from each side; the stem 28 projecting from what may be termed the outer side of the valve, being located in a bearing plate 95 29. Each bearing plate separates the outer part of the main chamber, or outer chamber, from a valve chamber, and each plate is adjustable lengthwise within the valve chamber, as herein shown this adjustment being 100 obtained by screw-threaded interengaging parts between the plate and the wall of the valve chamber, the showing of threads on the plate being omitted for sake of clearness. Each plate has a threaded stem 30 within 105 which a valve stem projects, the outer end of the plate stem being threaded to receive a locking cap 31 abutting against the casing

around the edges of the valve chamber. Each valve is held to its seat by a valve spring 32. One of the stems projecting from what may be termed the inner face of one of the valves is hollow and receives the stem projecting from the inner face of the opposite valve. In the construction herein shown the stem 33 from the valve 26 projects within the stem 34 from the valve 27 and the latter has a bearing at its inner end within a projection 35 rising from the bottom of the intake chamber 23. Passages 36 lead from each of the chambers 24, 25 into the crank chambers 14, 15 and a supply pipe 37 conducts the fuel to the chamber 23. Inlet passages 38 are located in projections 39 extending along the walls of the cylinders, these inlet passages conducting the fuel to inlet ports 40 through the wall of the cylinder to the interior thereof. Each of these ports has a bridge 41 diagonally arranged as plainly shown in Fig. 1, this bridge serving as a guide to prevent the piston or its packing from encountering the walls of the port. Each of the pistons is provided with a baffle 42 located on its upper end, this baffle projecting to such extent that it closely approaches the upper end of the cylinder in the upstroke of the piston. The exhaust ports from each cylinder lead to an exhaust pipe 44 which may discharge at any suitable point, in the construction herein shown this discharge being into the lower frame part 6. The upper end of the cylinders may be supported if desired by a frame member 45.

The construction of the valves enables the tension of the spring to be adjusted while the engine is running, so that it may be readily determined when the correct adjustment is obtained and the valves are working properly. This adjustment is performed by removing the locking cap 31 which gives access to the bearing plate 29 without opening the valve chamber. This bearing plate may then be turned until the proper pressure upon the spring is obtained when the cap is again placed in position, the screw-threaded engagement with the stem of the plate locking the latter in the position in which it has been placed.

We do not limit our invention as defined by the following claims to a device constructed exactly in accordance with the foregoing illustration and description of the preferred form in which the invention is shown and embodied, as these may be departed from to a greater or less extent without avoiding the invention.

We claim—

1. A casing having an intake chamber and a main chamber, the latter divided into valve and outer chambers, a bearing rising from the floor of said intake chamber, a valve located in said valve chamber, a stem projecting from the valve into said bearing, a

spring to force the valve against its seat, a plate closing the valve chamber and receiving the thrust of said spring, and means for adjustably positioning the plate.

2. A casing having an intake chamber and a main chamber, the latter being divided into valve and outer chambers, a bearing rising from the floor of the intake chamber, a valve located in the valve chamber, a spring to force the valve against its seat, a plate located within the main chamber and closing the valve chamber and receiving the thrust of said spring, means for adjustably positioning said plate, a stem projecting from the valve into said bearing, and a stem projecting from the opposite side of said valve into said plate.

3. A casing having an intake chamber and main chambers, the latter being each divided into valve and outer chambers, a bearing projection rising from the floor of the intake chamber, valves located in each of said valve chambers to control the inlets to the main chambers, stems projecting from each of the valves into said bearing projection, and means for forcing the valves against their seats.

4. A casing having an intake chamber and main chambers, the latter being each divided into valve and outer chambers, a bearing projection rising from the floor of said intake chamber, valves located within each of the valve chambers, a valve stem projecting from one valve into said bearing projection, a stem projecting from the opposite valve into the stem of the first mentioned valve, and means for forcing the valves against their seats.

5. A casing having closed valve chambers located therein, valves oppositely located in said chambers to control flow of fluid, a stem projecting from one of said valves, a stem projecting from the opposite valve and having a bearing in the first mentioned stem, means for forcing the valves to their seats, and means arranged to adjust the pressure upon the valves when said chambers are closed.

6. A casing having valve chambers, valves oppositely located within said chambers, springs pressing against said valves, a plate closing each of said valve chambers and receiving the thrust of a spring, means for adjustably positioning said plate, a stem projecting from one valve and having an opening therein, and a stem projecting from the opposite valve into the opening in the first mentioned stem.

7. A casing having a valve chamber and a bearing projecting from the wall of said chamber, a valve located in said chamber to control flow of fluid, a spring to force the valve against its seat, a plate closing the valve chamber and receiving thrust of the spring, means for adjustably positioning the

plate, a stem projecting from the valve into said bearing projection, and a stem projecting from the opposite side of said valve into said plate.

- 5 8. A casing having an inlet chamber, a bearing projecting within said chamber, valve chambers, valves located in each of said chambers to control the inlets thereto, stems projecting from each of the valves into said bearing projection, and means for forcing the valves against their seats.
- 10 9. A casing having an inlet chamber, a bearing projecting within said chamber,

valve chambers, valves located in each of said chambers, a valve stem projecting from 15 one valve into said bearing projection, a stem projecting from the other valve into the stem of the first mentioned valve, and means for forcing the valves against their seats.
